DESIGN FOR A CARPET.

SPECIFICATION forming part of Design No. 16,009, dated March 31, 1885.

Application filed February 12, 1885. Term of patent 3½ years.

To all whom it may concern:

Be it known that I, NORIC KOMORI, a resident of New York city, in the county and State of New York, have invented and produced, by 5 my own industry, genius, efforts, and expense, a new and original Design for a Carpet, of which the following is a full description, in connection with the accompanying photograph, which represents a face view of my new 10 design for a carpet.

This invention relates to a new ornamentation of the face of a carpet, oil-cloth, or analogous fabric.

In the accompanying photograph are represented the various parts which enter into 15 my new design.

a, b, and d are representations of fanciful flowers, between which are representations *e*

and *f* of fanciful leaves. Near these are representations *g* of serrated leaves. Near each 20 floral ornament *b* is also a veined leaf, *h*, containing a peculiar ornament, *i*.

j, k, and l are representations of fanciful flowers, which also occur on the design.

The different ornaments heretofore described are placed on the background, which contains, interspersed between them, grape-like clusters.

I claim—

The design for a carpet, the same consisting 30 of the figures *a, b, d, e, f, g, h, i, j, k, and l*, substantially as shown.

NORIC KOMORI.
